INVENTOR

F. A. Wells,
BY *P. F. Bowring*
his ATTORNEY

UNITED STATES PATENT OFFICE.

FRANK A. WELLS, OF NEW YORK, N. Y.

DESIGN FOR A BIDET.

SPECIFICATION forming part of Design No. 35,854, dated April 8, 1902.

Application filed February 10, 1902. Serial No. 93,456. Term of patent 14 years.

To all whom it may concern:

Be it known that I, FRANK A. WELLS, a citizen of the United States, residing in New York city, borough of Manhattan, State of New York, have invented and produced a new and original Design for a Bidet, of which the following is a specification, reference being had to the accompanying drawings, forming part hereof, wherein—

10 Figure 1 is a side elevation of a bidet embodying my design. Fig. 2 is an end view thereof. Fig. 3 is a plan view, and Fig. 4 is a bottom plan view, of the bidet.

15 The leading or material feature of my design consists in the shape or configuration of a bidet, wherein the bowl portion is rounded or swelled on the outer sides, and between the forward and back portions of said sides is a depressed portion, at the back portion there 20 being a rib provided with an outwardly-extending hub or projection, and beneath the swelled portions of the bowl is a jacket or wall extending along the sides and front and open at the back and provided along the sides 25 with depressed portions beneath the depressed portions of the bowl.

In the drawings the letter A indicates the bowl, which is rounded at the front and provided with rounded or swelled portions *a* at

the forward end and with rounded or swelled 30 portions *a*² at the rear portion, between the portions *a* *a*² on each side being a depressed portion *a*³, and above said portions of the bowl is a rim B, which is rolled or curved and is generally convex at the outer edge at the 35 front and rear and along the sides, and between the convex portions are concave portions *b*. At the back of the bowl is a rib C, which extends upwardly at *c* and has a projection or hub *d*. Beneath the bowl is a 40 jacket or wall D, which is curved at the forward and side portions and provided with depressions *e*, beneath the depressed portions *a*³ of the bowl, the jacket or wall D having an opening E at the rear through which appears 45 a depending curved horn F. Within the bowl its bottom G has a depression at *g* *g*², in which is an opening *f*, in line with the horn F, and behind said pocket the bottom G has a countersunk recess *h*. 50

I claim—

The design for a bidet, substantially as herein shown and described.

FRANK A. WELLS.
